(57) **CLAIM**

The ornamental design for a digital video camera as shown and described.

DESCRIPTION

FIG. 1 is a front view of a digital video camera showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a front view showing the open state of the stand thereof;

FIG. 8 is a rear view showing the open state of the stand thereof;

FIG. 9 is a top plan view showing the open state of the stand thereof;

FIG. 10 is a bottom plan view showing the open state of the stand thereof;

FIG. 11 is a left side view showing the open state of the stand thereof;

FIG. 12 is a right side view showing the open state of the stand thereof;

FIG. 13 is a front perspective view in the table-top use state of the stand thereof; and,

FIG. 14 is a rear perspective view in the table-top use state of the stand thereof.

The dash-dotted broken lines define the bounds of the claimed design; the evenly spaced broken lines show a digital video camera; all broken lines form no part of the claimed design.

1 Claim, 11 Drawing Sheets
